UNITED STATES PATENT OFFICE.

WILLIAM L. WALKER, OF NEW YORK, N. Y., ASSIGNOR TO WALKER SIGNAL & EQUIPMENT CORPORATION, OF NEW YORK, N. Y., A CORPORATION OF DELAWARE.

MICROPHONE.

Application filed August 12, 1921. Serial No. 491,715.

To all whom it may concern:

Be it known that I, WILLIAM L. WALKER, a citizen of the United States, residing in the borough of Manhattan, city, county, and State of New York, have invented certain new and useful Improvements in Microphones, of which the following is a full, clear, concise, and exact description.

My invention relates particularly to microphones for receiving and transmitting sound vibrations and is particularly adapted to the transmission of sound waves received through liquid media such as water, to telephones either directly or through amplifying devices now often used and well known in the art. My apparatus is particularly adapted to receive vibrations produced by submarine sound signaling devices and transmit the same to those aboard warships or other vessels whereby navigational or military information may be utilized.

The present microphones now in use are ill-adapted for use in submarine signaling on account of the great difficulty of being accurately matched and retaining their matched qualities, this being the primary requisite for obtaining accurate directive results.

For use in receiving submarine signals or sounds, microphones should be very ruggedly constructed, capable of being readily matched, of great durability and not liable to transmit variations except those impressed directly on the diaphragm, that is, lateral vibrations originating within the ship itself and communicated to the skin of the vessel should affect the microphones to the very smallest degree. Furthermore, microphones used for submarine signaling must be very uniform in their action and possess a standard degree of effectiveness which must be continuously maintained and not subject to variation or deterioration. Where microphones are used on opposite sides of a vessel for the purpose of indicating the direction of the source of sound, the microphones must be of substantially equal action or responsiveness to the sound waves and must maintain these characteristics to obtain satisfactory results.

All microphones now in use to a considerable extent in submarine signaling contain carbon particles and have mica diaphragms. These, however, are not entirely satisfactory

for submarine signaling on account of being fragile and unstable in their nature, owing to the use of parts which do not give uniformly variable resistance at the resistance varying points. On the contrary, the use of my improved microphone obviates these difficulties and the construction enables the microphones to be made substantially of one standard effectiveness or resultant action in converting the sound waves into corresponding electric waves to be transmitted to the telephone receiver.

Briefly stated, my improved microphone involves the use of a series of preferably thin carbon discs or plates placed face to face and under slight pressure between electrical conducting pieces or plates which preferably have pointed surfaces to give better microphonic contacts for the transmission of the current to the carbon discs or plates. The planes of the carbon discs referred to are preferably arranged parallel to the face of the receiving diaphragm so that lateral vibrations, that is, vibrations in the direction of the plane of the diaphragm or parallel thereto in the supporting parts, are not communicated to the discs in the direction of their axes. These carbon discs may be made of uniform thickness, hardness, size and fineness of the carbon, thereby enabling the action of the microphones to be rendered substantially uniform and constant as regards the conversion of the sound waves so as to cause similar variable resistances and thereby produce correspondingly variable electric currents. Furthermore, by varying the pressure of the respective carbon discs or their size and number, the respective microphones in a signal receiving installation can be set for any required resistance, current, and tone quality, which will enable them to receive in the most efficient manner a desired signal or sound and those most suitable for the particular type of the telephones or amplifying devices which may be desired to be used in connection therewith. The use of carbon discs under resilient pressure has been found to eliminate noises sometimes produced in other sensitive microphones whether used with or without amplifying tubes, particularly the so-called "frying" sound, which is produced when the microphone energizing currents of certain strengths are

passed through the microphone. We have found that no "frying" noise occurs over a large range of current in my improved microphone.

5 I have also found that varying the pressure, the size and number of the discs, materially aids in making the microphone resonant to desired periods of vibration, such as produced by apparatus used in sound 10 signaling, that is, by designing the diaphragm, the connecting parts and the number and size of the carbon discs, the microphone can be made to respond more perfectly to submarine signals of standard frequency 15 than to undesirable sounds caused by the water or noises originating aboard the ship, and thus the selectiveness or tuning of the microphone can be brought about to a high degree. The construction herein- 20 after described also results in a microphone that is very rugged and will stand a great deal of abuse without having its sound-electrical-converting properties affected or changed to any substantial degree, in conse- 25 quence of which the microphone is unusually reliable and constant in its action at all times.

Therefore, when separate microphones are constructed similarly with similar electric 30 characteristics they will have the same action or effect, there being no loose particles or grains or material to become displaced and thereby cause variable results.

Furthermore, my improved microphone 35 can be made as sensitive as any microphone available at the present time, or may be damped to almost any degree by varying the number and size of the plates or discs or the pressure thereon.

40 From the foregoing description, it will be seen since the microphones can be made with very uniform operating characteristics, they can easily be matched, especially when used accumulatively, that is, when used 45 in series or in parallel they will augment the received sound signals practically in proportion to the number connected together.

The simplicity of construction of this 50 microphone is such that any parts subject to injury or wear can be easily replaced and the same characteristics obtained as before being damaged.

I have found that this microphone repro- 55 duces speech or sounds with practically true tone or quality and furthermore the quality of tone is not affected by amplification.

Although I have referred to this microphone as being particularly adapted for use 60 in submarine signaling, it is obvious that it can be used equally well for other purposes and where other forms of microphones have been used.

The preferred form of my invention is 65 described in the following specification and

reference is made therein to the accompanying drawings forming a part thereof, in which:

Fig. 1 is a longitudinal sectional view of one form of my improved microphone, attached to a diaphragm as disclosed in my previous patent application, Serial No. 468,611, filed the 11th day of May, 1921.

Fig. 2 is an enlarged sectional view of the tube for supporting the carbon plates or 75 discs and contact plates of the microphone, showing the details thereof.

Fig. 3 is an end view of microphone tube and cap.

Fig. 4 is a plan view of one of the contact 80 plates between which the carbon discs are held.

Fig. 5 is a diametral sectional view of the contact plate of Fig. 4.

Referring to the drawing, the numeral 85 1 indicates a circular ring made of steel or similar resilient material preferably having the diaphragm 2 made integral therewith. This ring and diaphragm are applied to the circular opening in the side or skin of 90 a vessel by means of suitable flanged rings secured in position by bolts as indicated. The diaphragm 2 is so positioned to be flush with the outer surface of the side of the vessel thereby forming a part of the stream line surface of the hull and preventing sounds caused by eddy currents, and similar noises caused by local disturbances of the water as the vessel travels through the same. This construction is disclosed 100 in my said application, Serial No. 468,611, filed 11th day of May, 1921. A small projection or boss 3 is formed at the center of the diaphragm 2 and has a central screw 105 threaded recess adapted to receive one end of a small screw-threaded pin 4 carrying on its opposite end a cup-shaped receptacle 5 which parts are preferably made of a metallic material such as brass, steel, etc.

The small cup-shaped member constitutes 110 a socket which receives one end of a small insulation member 6 in the form of a cylindrical rod of condensation product of phenol or other insulating material, the opposite end of which enters a socket in the 115 boss 7 carried by a disc 8. The opposite surface of the disc 8 is preferably pointed or roughened as indicated at 8' in Figs. 4 and 5 and made as light as possible by boring small holes therethrough. This surface is 120 preferably formed by cutting transverse grooves at right angles to each other through the use of a 90° milling cutter and the holes 28 referred to are drilled at the bottom of the intersections of the grooves as clearly indicated in Fig. 4, but may be made in other ways.

As a support for the other parts constituting the active portions of the microphone exclusive of plate 8 a cylindrical tube 130

9 is provided, preferably made of insulating material or if not insulating then having an insulating layer on its interior surface. This surface should be smooth and free from any tendency to retard the free movement of the carbon discs. The tube 9 is supported in an internally screw-threaded ring 10 and is provided with an hexagonal flange 9' which abuts against said ring 10 and fixes the tube 9 in position. The ring 10 is supported by a plate 11 of material which is preferably flexible but non-elastic. For this purpose, I have found that a material resembling rubber coated cotton packing or belting is most desirable. This material is substantially waterproof, very durable, and non-resilient to a high degree. Through its use, I am enabled to prevent lateral vibrations transmitted by the skin 20 of the vessel being communicated to the supporting tube 9 containing the carbon discs constituting the microphone proper. This plate is attached to the supporting ring 10 in any suitable way such as by annular rings 25 12 to which the ring 10 is secured by means of machine screws 13, or equivalent device. The outer margin of the plate 11 is attached to the annular plate 14 which is clamped between the ring 1 and the clamping ring 15. Referring now to the parts within the supporting tube 9 (Fig. 2), a series of carbon discs 16 are set on edge or vertically arranged within the tube, the first one contacting with the roughened or pointed plate 30 8 and the last one contacting with a similarly pointed plate 17. This plate is provided with an outwardly extending lug 18 which receives the end of an insulated wire 19, which passes through the cap 20. The cap 20 is internally screw-threaded and adapted to engage the screw threads on the outer surface of the tube 9 and is provided with a series of longitudinal grooves 21 adapted to receive a rib 22 carried on the resilient arm 23 attached to the flange 9' of the tube 9. The rib 22 engaging the grooves 21, holds the cap 20 in any radial position without becoming loosened by vibrations or shocks transmitted to the tube. Between the 40 interior surface of the cap 20 and the plate 17, I insert the resilient pressure member which may be in the form of a spring or other well known part, as indicated by the numeral 24. This may be placed under compression by adjusting the position of the cap 20 and so produce a definite pressure between the series of carbon discs 16 as will be readily appreciated by considering Fig. 2. The electrical connections for introducing energizing current for the microphone may be conducted to the contacting parts in any suitable way, such as by the wire 25 passing through the plate 11, which wire enters the space between said plate and the 45 diaphragm and is attached to the socket 7

on the disc 8. The other terminal 19 may pass through the cap 20 and engage the lug 18; as above described, or in any other suitable manner.

As above indicated, plates 8 and 17, which are in contact with the opposite ends respectively of the series of carbon discs and under compression by the spring 24, each have similar contacting surfaces engaging the carbon discs. These surfaces are 50 grooved, roughened, or otherwise formed so as to have a plurality of individual projections for conducting the electrical current to the carbon resistance element. The function of the sharp pyramidal points is to 55 make a multiple microphonic contact with the carbon discs as distinguished from a single electrical contact. In practice I have found that by properly adjusting the compression of the spring 24, and using the point 60 contacts described, the sensitiveness of the microphone is greatly increased.

From a consideration of the above description, taken in connection with the drawing, the operation of my improved 65 microphone will be apparent without further explanation and the advantages set forth prior to the detailed description will readily be recognized. I do not wish to be understood as being limited to the details 70 of form or arrangement of parts herein set forth, for various changes may be made by those skilled in the art without departing from the spirit or scope of my invention.

What I claim and desire to protect by Letters Patent is:

1. In a microphone, a current varying member comprising a body of laminated carbon, and metallic plates having numerous definitely preformed contacting points 105 thereon and adapted to contact with opposite ends of said body for conducting electric current into and through said body.

2. In a microphone, a current varying member comprising a body of laminated carbon and conducting plates having numerous definitely preformed points thereon contacting with the opposite ends of said body for conducting electric current into and through 110 said body.

3. In a microphone, a current varying member comprising a series of thin carbon discs in contact with each other and bearing plates having numerous definitely preformed points thereon in contact with said discs at 115 each end of said series for conducting electric current into and through said plates.

4. In a microphone, a current varying member comprising a body of compressed homogeneous pieces of carbon, and recessed 120 bearing plates providing numerous projections contacting with the opposite sides of said pieces.

5. A microphone comprising a series of 125 conductive current varying elements and op-

- posed conducting parts having a plurality of minute definitely preformed contacting points engaging the outer elements of said series.
6. A microphone comprising a series of conductive current varying elements and including conducting parts having a series of sharp points contacting with adjacent elements of said series.
10. A microphone comprising a series of conductive current varying elements in the form of successive plates, opposed conducting parts having a series of sharp points contacting with the outer elements of said series, and means for producing resilient pressure on said elements between said parts.
15. A microphone comprising a series of conductive current varying elements in the form of successive plates, opposed conducting parts having a series of sharp points contacting with the outer elements of said series, a resilient member engaging one of said parts, a tube in which said member, parts and elements are contained, and an adjustable cap engaging the end of said tube and said resilient member and adapted to determine the pressure on said elements.
20. A microphone comprising, a series of conductive current varying elements in the form of successive plates, opposed conducting parts having a series of sharp points contacting with the outer elements of said series, a resilient member engaging one of said parts, an insulating tube in which said member, parts and elements are contained, means for varying the compression of said resilient member, and an insulating connector for uniting the other of said parts with the diaphragm of said microphone.
25. A microphone comprising, a series of conductive current varying elements in the form of successive plates, opposed conducting parts having a series of sharp points contacting with the outer elements of said series, a resilient member contacting with one of said parts, an insulating tube in which said member, parts and elements are contained, means for varying the compression of said resilient member, and an insulating connector for uniting the other of said parts with the diaphragm of the microphone.
30. A microphone comprising, a series of conductive current varying elements in the form of successive plates, opposed conducting parts having a series of sharp points contacting with the outer elements of said series, a resilient member contacting with one of said parts, an insulating tube in which said member, parts and elements are contained, means for varying the compression of said resilient member, and an insulating connector for uniting the other of said parts with the diaphragm of the microphone.
35. A microphone comprising, a series of conductive current varying elements in the form of successive plates, opposed conducting parts having a series of sharp points contacting with the outer elements of said series, a resilient member contacting with one of said parts, an insulating tube in which said member, parts and elements are contained, means for varying the compression of said resilient member, and an insulating connector for uniting the other of said parts with the diaphragm of the microphone.
40. A microphone comprising, a series of conductive current varying elements in the form of successive plates, opposed conducting parts having a series of sharp points contacting with the outer elements of said series, a resilient member contacting with one of said plates, a non-resilient insulating connector for uniting the other of said plates with the diaphragm of the microphone, an insulating tube in which said elements, plates and resilient member are supported, a screw threaded cap engaging said tube and adapted to determine the compression of said resilient member to fix the pressure between said elements and means for holding said cap in various positions axially.
45. A microphone comprising, a diaphragm, a hollow container, a series of conductive current varying elements therein, means for operatively connecting said diaphragm and said elements, means for transmitting electric current to and through said elements, and a flexible non-resilient supporting member carrying said container and adapted to confine the vibrations active upon said elements to those substantially normal to the said diaphragm.
50. A microphone comprising, a series of conductive current varying elements in the form of successive sheets or plates, means for transmitting electric current to and through said elements, a supporting tube therefor, and a flexible non-resilient supporting plate extending laterally from said tube and adapted to hold the latter in position and to confine the active vibrations to those substantially normal to the diaphragm of the microphone.
55. A microphone comprising, a series of conductive current varying elements in the form of successive sheets or plates, means for transmitting electric current to and through said elements, a supporting tube therefor, and a flexible non-resilient supporting plate extending laterally from said tube and adapted to hold the latter in position and to confine the active vibrations to those substantially normal to the diaphragm of the microphone.
60. A microphone comprising, a diaphragm, a hollow container, a series of conductive current varying elements therein, means for operatively connecting said diaphragm and said elements, means for transmitting electric current to and through said elements, and a flexible non-resilient supporting member carrying said container and adapted to confine the vibrations active upon said elements to those substantially normal to the said diaphragm.
65. A microphone comprising, a series of conductive current varying elements in the form of successive sheets or plates, means for transmitting electric current to and through said elements, a supporting tube therefor, and a flexible non-resilient supporting plate extending laterally from said tube and adapted to hold the latter in position and to confine the active vibrations to those substantially normal to the diaphragm of the microphone.
70. A microphone comprising, a series of conductive current varying elements in the form of successive sheets or plates, means for transmitting electric current to and through said elements, a supporting tube therefor, and a flexible non-resilient supporting plate extending laterally from said tube and adapted to hold the latter in position and to confine the active vibrations to those substantially normal to the diaphragm of the microphone.
75. A microphone comprising, a series of conductive current varying elements in the form of successive sheets or plates, means for transmitting electric current to and through said elements, a supporting tube therefor, and a flexible non-resilient supporting plate extending laterally from said tube and adapted to hold the latter in position and to confine the active vibrations to those substantially normal to the diaphragm of the microphone.

WILLIAM L. WALKER
